UNITED STATES PATENT OFFICE.

THOMAS P. SEASTRUKN, OF DALLAS, TEXAS.

EMBLEM STRUCTURE.

1,340,465.

Specification of Letters Patent. Patented May 18, 1920.

Application filed May 9, 1918. Serial No. 233,438.

To all whom it may concern:

Be it known that I, THOMAS P. SEASTRUKN, a citizen of the United States, residing at Dallas, in the county of Dallas and 5 State of Texas, have invented certain new and useful Improvements in Emblem Structures, of which the following is a specification.

This invention relates to new and useful 10 improvements in emblem or insignia structures and the manufacture of the same.

The purpose of the invention is to produce a structure in which a multiplicity of emblematic parts are mounted on a base of 15 particular construction in a novel manner.

In carrying out the invention a rigid 20 mounting plate or form is provided and shaped to the general contour of the emblem or insignia to be produced. Cloth or other material is placed over the face of the 25 form and secured on the back thereof. Emblems or insignia parts are stamped from metal or the like, but instead of being flat are embossed. These parts are provided 30 with prongs or the like and holes for the latter are punched through the cloth covering and the metal form. Those portions of 35 the prongs projecting on the back of the form are bent down against the same and may be covered by the cloth if desired. Suitable means for securing the structure on the clothing of the wearer may be added. By this arrangement bright metal parts may be mounted on a dark contrasting cloth 40 background and the whole structure expeditiously and artistically manufactured.

The invention will be more readily understood from a reading of the following specification in which an example of the invention is described and by reference to the accompanying drawing, in which:

Figure 1 is a view of a structure made in accordance with this invention,

Fig. 2 is a rear elevation of the same,

Fig. 3 is a transverse sectional view on the line 3—3 of Fig. 1, and

Fig. 4 is a similar view on the line 4—4 of Fig. 1.

In the drawings the numeral 1 designates 50 a metal base or form. This base may be made of other rigid material, but metal is preferable. The base is cut or stamped and given the general shape of the emblem or insignia to be formed.

55 A piece of ornamental cloth or equivalent material 2 is cut with an ample allowance

for covering the face of the base and lapsing over on the back thereof. This covering forms the back-ground and conceals the base. Metal emblem plates 3 and 4 respectively are mounted on the cloth covering. In the present instance the plate 3 is made in the form of shield, while the plates 4 represent wings and are disposed on each side of the shield, the adjacent edges of the 65 wings conforming to the contour of the edges of the shield and being separated therefrom so that the back-ground shows therebetween. The general contour of the base conforms to that of the plates 3 and 4 70 so that each part has a marginal panel formed by the background cloth.

The plates 3 and 4 are embossed so as to cause them to stand out in bas-relief and whereby they may be easily stamped from 75 dies. The plate 3 has prongs 5 at its upper and lower ends; while each plate 4 has prongs 6 at its inner and outer ends. Holes are punched through the covering 2 and the base 1 to receive these prongs. The marginal edges of the plates 3 and 4 are either bent into flanges or merged into a flat surface so as to lie in contact with the covering. Those portions of the prongs projecting from the rear side of the base are bent 85 down onto the base as shown and the plates 3 and 4 held in firm contact with the cloth covering.

After the prongs have been bent down the edges of the cloth covering may be united by 90 cross-stitching as at 7, or secured in any other manner. A pin 8 may be mounted on the rear side of the base or any other suitable garment fastening could be employed.

This structure produces an emblem which 95 may be readily changed from one suit to another without defacing and permits the making of a very handsome insignia by the use of precious metals and jewels. It is substantial and readily lends itself to manufacture in large quantities at a minimum cost.

One of the important features of this structure is that by bending up the prongs the emblematic parts may be removed and polished and the cloth covering replaced or 105 cleaned, after which the parts may be replaced.

What I claim, is:

1. The improvement in the manufacture of insignia which consists in first forming 110 the design from a plurality of detachably arranged metallic plates, each plate being

5 stamped or embossed with the design desired, then forming the rigid base with a contour required by the design, then covering said base with cloth and finally uniting the plates to the base by fasteners traversing the cloth and united to the rear face of said base.

2. In an insignia, a series of embossed metal plates, a plurality of prongs project-

10 ing from the rear concave face of each plate, a rigid base perforated to receive the prongs, and a covering of fabric inclosing the base, said covering adapted to be traversed by the prongs in the fastening of said plates to said base.

15

In testimony whereof I affix my signature.

THOMAS P. SEASTRUNK.
